MATERIAL WORKING APPARATUS

Bernhard Norem, Chicago, Ill., assignor to
Western Electric Company, Incorporated, New
York, N. Y., a corporation of New York

Application December 31, 1931, Serial No. 584,169

14 Claims. (Cl. 164—33)

This invention relates to material working apparatus, and more particularly to apparatus for ejecting blanked articles from blanked material.

The primary object of this invention is to provide a simple, efficient and readily adjustable and adaptable apparatus whereby blanked articles of various shapes and dimensions may be ejected from blanked material.

In accordance with one embodiment of this invention, as used in connection with a compound punch and die, there is provided an apparatus comprising means for supporting a strip of blanked material carrying the blanked articles as it issues from the punch and die into engagement with an element or a plurality of elements yieldably and adjustably mounted to suit the shape and dimensions of the articles to be ejected from the material, the element or elements continuously bearing against the blanked material and pressing the articles individually therefrom and through an aperture in the material supporting means.

Other objects and advantages of this invention will more fully appear from the following detailed description taken in connection with the accompanying drawing, in which

Fig. 1 is a fragmentary elevation of a compound punch and die with one embodiment of the article ejecting mechanism of this invention associated therewith;

Fig. 2 is a plan view of the ejecting mechanism shown in Fig. 1;

Fig. 3 is an enlarged vertical section taken on the line 3—3 of Fig. 2;

Fig. 4 is an end view of another embodiment of the roller supporting portion of the ejecting mechanism shown in Fig. 3, and

Fig. 5 is a plan view of Fig. 4.

In the accompanying drawing, referring particularly to Fig. 1, one embodiment of this invention is illustrated as used in connection with a compound blanking and perforating punch and die indicated at 10 which is operatively connected to a punch press, a frame 11 and a reciprocating ram 12 of the punch press being fragmentarily illustrated. The compound blanking and perforating punch and die 10 and the punch press are of a well known type and the details of construction thereof have been omitted from the present application, since it is not essential to a complete understanding of the present invention.

It is believed sufficient herein to state that in the operation of the punch and die 10 of the type mentioned, a strip of material 13 is intermittently advanced in a horizontal plane therethrough from

right to left as shown in Fig. 1 by means well known in the art. At the termination of each advance movement of the material 13, the punch and die 10 is operated during an advance and return movement of the punch press ram 12 to perforate and blank an article 14 (Fig. 3) out of the material and reinsert the article therein.

The article ejecting apparatus, indicated generally by the numeral 17 (Fig. 1) in the present embodiment thereof as used in connection with a material working apparatus of the type of above referred to punch and die, is supported on a shelf or bracket 18 fixed to the punch press frame 11 at the left side thereof. Secured to the upper surface of the bracket 18 by means of 30 screws 19, one of which is indicated in Fig. 1, is a base plate 20 for the ejecting apparatus 17. The base plate 20 at opposite ends is provided with arms 21 and 22 (Figs. 1 and 2) between which and resting on the upper surface of the 35 base plate is an interchangeable plate 25 which supports and guides the strip material and which is clamped to the base plate by a pair of screws 40 26 threaded through the arm 21 and engaging the adjacent end surface of the plate 25, the 45 opposite end of the latter being thereby clamped against the arm 22. Formed in the upper surface of the plate 25, intermediate the arms 21 and 22, is a depressed surface 27 which lies substantially in the plane of the under surface of 50 the strip material 31 which is intermittently advanced from the punch and die 10. The material 31 is supported on the surface 27 and its lateral edges extend into guide channels 28 (Fig. 3) 55 provided in the die plate 25 at each side of the 50 surface 27. Formed in the surface 27 of the plate 25 is an aperture 29 to permit the articles 14 ejected from the strip material 31 to drop through a comparatively large aperture 30 provided in the base 20 and into an aligned aperture 31 in the bracket 18 to a receptacle (not shown). The strip material supporting and guiding plate 25 is interchangeably mounted on the base plate 20 so that other plates 25 constructed to accommodate strip material 13 of 60 different widths or to accommodate articles 14 of different sizes or contours, the different plates 25 having the guide channels 28 spaced to suit a particular width of strip material and apertures 29 to suit the particular size or shape of the 65 article which is being ejected from the strip material.

Mounted above and fixed to the plate 25 at opposite sides thereof are mounting bars 33 which are supported upon the upper ends of inter- 70

changeable cylindrical columns 34, the bars and the columns being fixed to the plate 25 by screws 35 passing through the bars and columns and threaded at their lower ends 5 into the arms 21 and 22. Supported between the bars 33 and secured thereto for longitudinal and lateral adjustment is a mounting bar 36 for a roller plunger assembly 37. The opposite ends of the bars 36 are bifurcated and extending between the furcations at each end is a bolt 38 which is inserted in one of a series of spaced apertures 40 formed in each of the bars 33. The bolts are screwed up tight after the desired positioning of the bar 36 longitudinally and laterally of the strip material 13 in accordance with the particular position of the articles 14 in the strip material.

Referring particularly to Fig. 3, the roller plunger assembly 37 in one embodiment thereof comprises a body member 41 having an externally threaded stem portion 42 and a head or nut portion 43. The member 41 is threaded into an opening in the bar 36 for vertical adjustment and is maintained in adjusted position by a pair of lock nuts at either side of the bar 36. Slidable in a rectangular shaped aperture 46 formed in the member 41 is a shouldered rod which has a threaded reduced portion 48 at its upper end, a cylindrical reduced portion 49 at its lower end and an intermediate rectangular shaped portion 50 fitting the aperture 46 in the member 41. Secured to the lower end of the cylindrical rod portion 49 is a roller supporting bracket 53 formed with a split collar portion 54 (Fig. 1) which is clamped to the rod portion 49 by a screw 55. Journaled in a bifurcated lower portion of the bracket 53 is a roller 56 which when the ejecting apparatus is in use continually bears upon the strip of material 13 as it is advanced thereunder. Surrounding the cylindrical rod portion 49 is a compression spring 57 opposite ends of which bear against washers surrounding the rod portion 49 and engaging the lower and upper end surfaces of the body member 41 and the bracket 53. Threaded onto the upper rod portion 48 is a hand grip member 60 provided with a rectangular or oblong portion 61 the under surface of which by engaging the upper surface of the head 43 determines the lower limit of motion of the roller 56. The hand grip member 60 also serves to hold the roller 56 in its inoperative position. For doing this it is drawn upwardly and turned a quarter turn so that its lower portion 61 rests on a pair of pins 62 mounted in the head 43.

In adjusting the parts just described the member 41 is adjusted vertically to a position in which the desired tension is placed on the roller 56. The hand grip member 60 is then adjusted vertically to a point where the roller 56 in its lowermost position extends far enough to press the blanks from the strip of blanked material but not so far but that it will readily roll up the side of the opening upon further movement of the strip material. When the member 60 is being rotated to make this adjustment it is raised sufficiently to clear the tops of the pins 62.

In Figs. 4 and 5 another embodiment of the roller bracket portion of the ejecting apparatus hereinbefore described, is illustrated which is used in another setup of the apparatus for ejecting articles of greater length than the article 14 of Figs. 1, 2 and 3. Referring to Fig. 4, a bracket 65 which is interchangeable with the bracket 53, hereinbefore described, on the cylindrical rod

portion 49 carries a rod 66, which may be square in cross-section, adjacent its lower end, the rod extending horizontally an equal distance at each side thereof. Adjustably carried upon each portion of the rod 66 is a roller bracket 67, the brackets 67 being held in their adjusted positions by set screws 68. The brackets 65 and 67 are formed so that they may be clamped to the rod portion 49 and the rod 66, respectively, in a manner similar to that described in connection with the bracket 53. The lower end of the bracket 65 is formed with a cylindrical portion 69 for supporting another roller bracket similar to the brackets 67 when it is desirable to provide three rollers due to the length of the article being ejected or other characteristics thereof. It will be obvious that either the two or three roller arrangement may be used to eject articles from material wherein two or three articles are blanked from the material, the articles extending either laterally or longitudinally of the material. In case the articles are formed in an angular direction in the strip of material 13 the roller brackets 53 and 65 may be adjusted on the rod portion 49 to support the roller or rollers 56 to correspond with the position of the articles in the strip of material. When adapting the ejecting apparatus for an article of greater length by means of the embodiment illustrated in Figs. 4 and 5, it is also necessary to mount another strip material supporting 100 and guiding plate 25 on the base plate 20 which may be readily accomplished in the manner previously described. Also, due to the greater height of the roller bracket assembly illustrated in Figs. 4 and 5, the mounting bars 33 will have to be supported at a correspondingly greater height. This may be easily provided for by removing the cylindrical columns 34 and mounting columns of a suitable length.

It is believed that the operation of the herein described apparatus will be clearly understood from the above description wherein the several embodiments thereof have been described for use in the ejecting of the articles 14 from the strip of material 13 issuing from the compound blanking 120 and perforating punch and die 10. Briefly described, the operation of the apparatus after adjusting and adapting it to the particular dimensions of the strip of material and the articles or the arrangement of the articles supported therein as hereinbefore described is as follows: In the intermittent advance of the strip of material from the punch and die 10 the articles 14 successively pass underneath the spring pressed roller or rollers 56 which continuously bear on the strip of 130 material and as each article comes into engagement with the roller or rollers, it is pressed or ejected individually from the material and it passes through the apertures 30 and 31 formed in the base 20 and the bracket 18, respectively, to a 135 receptacle (not shown).

Although the preferred embodiments of this invention have been described for use in connection with the ejection of blanked articles supported in blanked strip material from the material as it 140 issues from a material working apparatus, such as a compound punch and die, it will be understood that the invention is capable of other applications within the scope of the appended claims.

What is claimed is:

1. In an apparatus for ejecting blanked articles from blanked material, means for supporting the material, and a pressure element engaging the material arranged directly opposite the material supporting means and effective upon a 150

- relative sliding movement between the element and the material for engaging the articles to eject them from the material through an aperture in the support.
- 5 2. In an apparatus for ejecting blanked articles from blanked material, means for supporting the material, and a spring pressed element continuously engaging the material and effective upon a relative movement between the element and the material for engaging the articles to eject them from the material.
- 10 3. In an apparatus for ejecting blanked articles from blanked material, means for supporting the material, a reciprocably mounted spring pressed plunger carrying a roller engaging the material and effective upon a relative movement between the roller and the material for engaging the articles to eject them from the material, and means for adjusting the pressure of the plunger and thereby the roller against the material.
- 15 4. In an apparatus for ejecting blanked articles from blanked material, means for supporting the material during a longitudinal advance thereof, and a reciprocably mounted spring pressed plunger carrying a member having a rolling engagement with the advancing material and effective to eject the articles from the material during its advance.
- 20 5. In an apparatus for ejecting blanked articles from blanked material, means for supporting the material, a reciprocably mounted spring pressed plunger carrying a roller engaging the material and effective upon a movement of the material past the roller for engaging the articles to eject them from the material, means for adjustably supporting the plunger relative to the plane of the material, and means for adjusting the pressure of the plunger and thereby the roller against the material.
- 25 6. In an apparatus for ejecting blanked articles from blanked material, a base plate, means interchangeably mounted thereon for supporting and guiding material having certain dimensions and carrying therein articles blanked therefrom of a particular size during a longitudinal advance thereof, and an element yieldably engaging the material and effective to eject the articles successively from the material at a predetermined position thereof through an aperture provided in the supporting and guiding means.
- 30 7. In an apparatus for ejecting blanked articles from blanked material, means for supporting the material, an element yieldably engaging the material and effective upon a relative movement between the element and the material for engaging the articles to eject them from the material, means for supporting the element, means rotatably mounted on the element for moving the same upon the supporting means out of operative engagement with the material, and means carried by the supporting means and cooperating with the means rotatable on the element when the latter means is predeterminedly rotated after a withdrawal of the element from operative engagement with the material for retaining the element in its inoperative position.
- 35 8. In an apparatus for ejecting blanked articles from blanked material, means for supporting the material, a spring pressed plunger, and a plurality of elements adjustable on the plunger at either side thereof and in a direction at right angles to its longitudinal axis for engaging the material and effective upon a relative movement between the elements and the plunger and the material for engaging the articles to eject them from the material.
- 40 9. In an apparatus for ejecting blanked articles from blanked material, means for supporting the material, means for adjustably supporting in spaced relation with the material a spring pressed plunger, means for adjustably mounting on the plunger at varying distances from and at each side of its longitudinal axis a plurality of rollers for engaging the material and effective upon a relative movement between the rollers and the plunger and the material for engaging the articles to eject them from the material, and means on the plunger for supporting a roller to be arranged between the aforesaid rollers and likewise for engagement with the material.
- 45 10. In a material working apparatus, means for forming articles from sheet material advanced thereto, and means for thereafter ejecting the formed articles mounted therein from the material as it is advanced therefrom, comprising means for supporting the material in its advance from the forming means, and a spring pressed plunger engaging the material advancing from the forming means and effective to eject the articles from the material.
- 50 11. In an apparatus for ejecting blanked articles from blanked material, a base plate, means interchangeably mounted thereon for supporting and guiding material having certain dimensions and carrying therein blanked articles of a particular size, and an element yieldably engaging the material and effective upon a relative movement between the element and the material for engaging the articles to eject them from the material.
- 55 12. In an apparatus for ejecting blanked articles from advancing blanked material, a supporting member over which the material is advanced, and an element movable at an angle to the path of movement of the material and bearing on the material during its movement over said supporting member to eject the blanked articles from the advancing material.
- 60 13. In an apparatus for ejecting blanked articles from blanked material, means for supporting the material, and a pressure element having a sliding engagement with the material for engaging the articles to eject them from the material.
- 65 14. In an apparatus for ejecting blanked articles from advancing blanked material, means for supporting the material, and means carried thereby and effective during a relative movement between the material and said supporting member for yieldably engaging the material to eject the blanked articles from the advancing material.

BERNHARD NOREM. 140
